MOULD FOR THE CENTRIFUGAL CASTING OF PIPES AND OTHER PIECES

Pierre Boissou, Pamiers, France, assignor to Societe Metallurgique Ariegoise et Lorraine, Pamiers, France, a French body corporate

Application April 20, 1953, Serial No. 349,605

Claims priority, application France April 21, 1952

7 Claims. (Cl. 22—65)

The present invention relates to the centrifugal coating of metal tubular pieces from in particular steel.

In known processes, the molten metal is generally introduced in the form of a jet directly into a substantially horizontal mould which is rotative about its longitudinal axis and is open at at least one end. The metal is driven in rotation by the mould and, as it is then subject to centrifugal force, is thrown against the walls of the mould and is caused to solidify upon contact with these walls. Owing to its inertia, the rotative movement of the metal varies progressively; at the commencement of rotation only the metal in immediate contact with the mould is driven in rotation, then this metal in its turn progressively drives in rotation the metal situated towards the centre of the poured metal. There occurs, then, a certain amount of concentric slip between the "layers" of metal; this slip diminishes until the layers furthest from the mould walls are driven at a speed equal to that of the rotation of the mould. This effect is particularly noticeable when centrifugally casting tubes having a wall thickness of the order of 40 mm. and more and, furthermore, when casting metals that undergo a slow solidification. In certain cases, at the start of the centrifugal casting, when the metal driven in rotation has not yet attained the upper generatrix of the mould and is, therefore, formed of a closed layer having a circular cross-section, the layer of metal falls towards the lower generatrices of the mould and splashes or spatters the metal inside the mold. In any case, the jet form of casting always creates splashing. As a consequence of the foregoing phenomena, a certain lack of homogeneity in the crystalline structure of the metal in the direction of the thickness of the piece is sometimes to be observed. This may be explained by the fact that the solidification of the outer layers had already commenced at the time when the inner layers were not being driven in rotation at the same speed as the mould. Globular crystals are to be found in the metal, which are larger than normal neighbouring crystals. This, it would seem, is due to the fact that the crests of the crystals which form during the solidification in a radial direction are broken off by the relative sliding or slip of the interior layers, macroglobulites developing from these broken-off crusts. Furthermore, there are also present in the thickness of the cast piece cold globules which result from the above-mentioned splashing and are embedded in the metal.

In an attempt to remedy the foregoing disadvantages, it has been proposed to subject the metal to a movement of rotation at a speed at least substantially equal to that of the mould before it is introduced into the mould. This is achieved by placing at the entrance to the mould a rotative distributor which subjects the molten metal running towards the mould to the desired rotation. In the known devices for putting this method into effect the distributor discharges into the mould through a large central opening through which cold air entering through the pouring aperture provided at the entrance of the distributor may reach at each instant during the entire period of pouring and solidification of the metal, the

2

interior of the mould. From the foregoing it is clear that in the known processes there is a continual renewing of the atmosphere inside the mould. Owing to this renewing of the atmosphere the inner surface of the moulded piece is subject to a cooling effect and is thereby solidified. The moulded piece solidifies, therefore, from its inner and outer surfaces. There results a formation on the inner surface of the moulded piece an internal shrinking which in certain cases may bring about a cylindrical separation which produces two tubular portions one inside the other. In any case, the presence of the two cooling surfaces prevents the total decantation of the inclusions (slag) and the degassing of the molded piece which results in the presence of air bubbles.

The invention has for its object to provide an improved rotative mould, this mould being of known rotative type in which the moulding chamber communicates with a distributor which forms a chamber provided with an orifice on the upstream side of the feed through which the molten metal is passing and is given thereby a speed of rotation equal to that of the mould.

According to the invention, the moulding chamber is closed at its end remote from the distributor so that no entry of air can occur and it communicates at its other end with the chamber of the distributor through apertures provided adjacent the periphery of a transverse screen introduced between the two chambers and taking part in their rotation, the points of these apertures the furthest from the axis of rotation of the mould assembly being substantially on a level with the inner surface of the moulding chamber and the radial dimension of these apertures being at the most equal to the radial thickness of the part of the piece to be cast which is adjacent the screen. As a result of this arrangement, these apertures are flooded or are submerged by the molten metal at least at the end of the pouring and prevent any entry of cold air from the distributor and its own entry aperture so that the poured piece does not tend to cool in the centrifugal direction from its central through-bore. In other words, during the whole of the cooling period the interior of the mould has an enclosed atmosphere.

Other features and advantages will be apparent from the ensuing description in which:

Fig. 1 is an elevational view of a mould according to the invention,

Fig. 2 is an axial longitudinal section of the mould shown to a larger scale,

Fig. 3 is a fragmentary view of the side of the transverse screen provided in the mould, this screen being viewed from the side situated in the plane 3—3 in Fig. 2 and in the direction indicated by the arrows.

Fig. 4 is a radial sectional view of this screen on line 4—4 of Fig. 3,

Fig. 5 is a view of the diffuser from the side thereof situated in the plane 5—5 in Fig. 2,

Fig. 6 is a longitudinal radial section of a modification of the screen and diffuser,

Fig. 7 is a section of the diffuser on line 7—7 in Fig. 6,

Fig. 8 is a sectional view similar to that in Fig. 6 of another modification of the screen and diffuser,

Fig. 9 is a sectional view on line 9—9 in Fig. 8,

Fig. 10 is a cross-sectional view of the mould showing a modification of the gas outlet apertures, and

Fig. 11 is a diagrammatic view in partial vertical section of a device for casting in an enclosed atmosphere in accordance with the invention.

In the embodiment shown in Figs. 1 to 5, the mould according to the invention comprises a mould body constituted by a shell 1 provided on its inner face in this example with a refractory lining 2, for example of sand. The surface 2^a of the moulding chamber thereby formed corresponds to the exterior shape of the cast tubular piece

to be obtained. The shell 1 is provided externally with two rolling surfaces 3, 3^a which rest on two pairs of rollers 4, 4^a, each pair being fixed to a longitudinal shaft 5 journalled in bearings 6. One of these shafts is capable of being driven in rotation by any device, for example, an electric motor 5^a, so that the mould rotates, for example, in the direction of arrow *f*. The horizontal axis XX of the mould may be horizontal or preferably make a slight angle of about 5% (4°) with the horizontal, the end situated at the right in Figs. 1 and 2 being in this case the higher.

The shell 1 is closed at one of its ends, i. e. that on the left in Figs. 1 and 2, by means of a device comprising a cup 7 fixed to the mould by means of screws 8 and provided with an axial aperture 9 in which slides the cylindrical boss 10 of a plate 11 housed in the cavity of the cup 7. This cavity, which faces the moulding chamber, is provided with sand 12 superimposed on the plate 11. A number of longitudinal passages 13 extend through the plate 11 and the sand 12. At the same end of the shell 1 is disposed an end plate 14 held by a number of screws 15. This plate is provided with a tapped hole 16 in which is screwed a rod 17 held to the end face of the head 10 and provided at its other end with a head and radially disposed arms 18. By screwing the screw 17 into the tapped hole 16, the plate 11 is displaced in the mould towards the right. The end plate 14 is also provided with a number of valves 19 which open under the action of a slight over-pressure inside the mould, so that the space enclosed between the end plate 14 and the cup 7 may be put into communication with the atmosphere.

At its other end, the shell 1 is provided with an extension which forms the chamber for the prior rotation of the molten metal. This chamber will be termed the "distributor" in the ensuing description. This distributor D comprises a hollow body 20, preferably of metal, which has a conical or like shape and is provided on its inner face with a refractory lining 21 of, for example, clay. The body 20 is open from one end to the other and its large opening is situated adjacent the shell 1. The small opening, concentric with the longitudinal axis XX of the mould, is in a preferred embodiment provided with a ring 22 of a refractory material such as, for example, silico-clay.

Between the distributor D and the mould is disposed a flanged ring 23 provided on its inner periphery with an annular rib or wall 24. The inner edge of this wall 24 is provided with an annular recess or rabbet 25 whose inside diameter is greater than the largest outside diameter of the tubular piece the machine is adapted to mould. A screen E essentially constituted by a detachable disc 26 and its refractory covering 29 is housed in this recess 25. The recess 25 is provided on the inside face of the wall 24 relative to the mould so that the disc 26 is free to move towards the left, i. e. towards the shell 1, but is prevented by the facing wall of the recess 25 from moving towards the right. The members 24 and 26 are temporarily held together by means of an alloy key 27 which melts at a much lower temperature than the metal to be moulded. A number of apertures 28 are provided around the periphery of the disc 26; these apertures overlap the annular wall 24 and put the inside of the body 20 into communication with the inside of the mould. The two sides of both the annular rib 24 and disc 26 as well as the apertures 28 are provided with refractory sand 29, which finally reduces the diameter of the apertures 28 to form apertures 28^a having a diameter *d*. As stated, disc 26 and its refractory covering 29 form the aforesaid movable screen E. The apertures 28^a are so arranged that they are enclosed within a circle whose diameter is substantially equal to the inside diameter of the moulding chamber in the region of the screen and the diameter *d* of the apertures is less than the thickness of the piece to be moulded in the machine whose inner face is represented by the line *mm* (Fig. 2). The

shell 1, the ring 23, and the distributor D are fixed together by means of bolts 30 and nuts 31.

The lining 21 of the distributor D includes ribs 32 (Figs. 2 and 5) in a number equal to that of the apertures 28 in the screen E and are disposed in front of the solid portions of the screen situated between the apertures 28. These ribs have a radial height *h* which is at least equal to the effective diameter *d* of the apertures 28 and their profile is dissymmetrical, their larger slope being directed in the direction of arrow *f*.

The machine operates in the following manner:

The mould is rotated about its horizontal axis XX in the direction of arrow *f*. The molten metal contained in a ladle 33 (Fig. 1) is introduced into the distributor D through the ring 22 by means of a pouring gate 34. The feed flow is adjusted in the following manner. At the start of the pouring, the rate of flow is much higher than the flow allowed by the apertures 28^a so that the latter are rapidly flooded. The liquid flow from the ladle is then reduced to a flow substantially that through the apertures 28^a so as to prevent an overflow of the diffuser while maintaining the level of the liquid metal in the distributor above that of the apertures 28^a. The molten metal flows along the inner face of the lining 21 of the distributor and is rapidly driven in rotation by the ribs 32 at a speed equal to that of the mould. Owing to the conical shape of this face, the metal is subject to a longitudinal component directed towards the shell 1. The metal flows, then, towards the interior of the shell 1 through the apertures 28^a. Since the metal is driven in rotation in the distributor D, when it enters the shell 1 it is subject, relative to the latter, to only a single component of speed parallel to the axis XX. The metal which flows into the moulding chamber is, then, subject to only the action of centrifugal force and undergoes no peripheral slip relative to the inner face 2^a of the mould. There is, therefore, a complete suppression of splashing inside the moulding chamber or, in other words, the metal is "turbined" in the distributor D at the same speed as the mould before it enters the shell 1.

It might be mentioned that owing to the fact that the level of the metal in the distributor rapidly exceeds that of the apertures 28^a, which, as hereinbefore mentioned,

are then flooded, the pouring is effected direct from the molten metal itself thereby preventing the impurities

which float inside the distributor chamber on the surface of the molten metal from entering the moulding chamber.

At the end of the pouring, the metal levels in the distributor and in the moulding chamber equalize along the line *mm* (Fig. 2).

During the filling of the mould, the air or the gases contained inside the mould heat upon contact with the molten metal, expand, and tend to increase the pressure of the atmosphere inside the mould. These gases escape through the passage 13 and the valves 19. The pouring aperture 22 is practically closed at the start of the pouring by the flowing metal and the submersion of the apertures 28^a very rapidly completely closes the mould and thereby prevents any entry of air therein. Thus, there is no danger of the inner surface of the molten metal contained in the

mould cooling, for the temperature of the air existing in the mould very rapidly attains a temperature very near that of the metal. The only cooling which could possibly occur is that caused by the contact of the metal with the inner face 2^a of the mould on the one hand, and the

cooling action of the end plate 11 and the screen E on the other hand; these latter are already heat-insulated by the refractory sand lining provided thereon which has such thickness that their cooling effect is negligible relative to that of the inner cooling surface 2^a of the mould.

The cooling, therefore, progresses radially and in the centripetal direction from the outer surface of the moulded piece towards the inner surface thereof.

When, as a result of the cooling effect of the mould, the metal completely solidifies, the rotation of the mould is discontinued. During the subsequent shrinkage of the

metal, the head 18 is rotated so as to urge the plate 11 toward the right (Fig. 2) and thereby subject the end of moulded metal remote from the plate 11 to a longitudinal compression. The displacement of the plate 11 is made possible by the breaking of the sand lining 12 around the periphery of the plate. By means of this compressing operation, the appearance of internal stresses which often create cracks caused by the shrinkage of the piece is prevented. Furthermore, at the pouring head end of the mould, the key 27, which connects the disc 26 of screen E to the annular wall 24, has, at the end of the moulding operation, already melted under the action of the heat, and the screen E, which is held between the piece and the dead head, solidified in the distributor and free in the direction of the moulding cavity, is free to follow the direction of shrinkage of the piece and the formation of cracks in this region is also prevented.

When the piece has cooled down, the distributor D is unbolted and is easily withdrawn towards the right thereby enabling the moulded piece to be extracted from the mould by exerting a pull on the dead head.

During this latter operation, the screen E is withdrawn with the piece. The ring 23 may then be withdrawn by sliding it towards the right. To free the disc 26 from the piece, it suffices, after having opened out the feed apertures 28^a, to separate the dead head from the piece by means of a welding torch which cuts through the cylindrical solidified portions of metal connecting these two parts.

By means of this casting process as hereinbefore explained, the metal that enters the moulding chamber i. e. the piece being moulded is driven in rotation at a peripheral speed substantially equal to that of the mould and there occurs no turbulence which would risk causing splashing or the formation of oxidized cold globulus. Furthermore, there is no relative, concentric, slip between the layers of metal from which might result ruptures of the metal crystals during the cooling period. Owing to the fact that the solidification occurs in an enclosed mould wherein there exists absolutely no cooling surface other than the wall of the mould itself, this solidification occurs only from the exterior towards the interior, thereby eliminating any possibility of a formation of inclusions, blow-holes, etc. Thus, the formation of macroglobulites is prevented and the pieces exhibit throughout their thickness an absolutely sound structure devoid of crystal rupture or heterogeneity of any kind. Moreover, the pouring of the metal from its source eliminates any presence in the cast piece of any impurity or slag. It is noteworthy that owing to the lack of slip of the molten metal on the inner surface of the mould, no abrasion of this surface occurs, which prevents any inclusion of sand in the cast pieces, which, when withdrawn from the mould, exhibit a very clean and regular outer surface.

In the above-described embodiment, the apertures 28^a have their axes disposed parallel to the axis XX of the mould, but they may, of course, be inclined in the direction of rotation or in the opposite direction so as to accelerate or decelerate the speed of entry of the molten metal into the moulding chamber.

According to the modification shown in Figs. 6 and 7 the distributor 35 in the shape of a conical cup comprises on the side of its large base an annular groove 36 constituting a recess in which is housed a screen 37. The unit is located in a machined recess 38 provided at the end of the shell 39, the screen 37 being held between the bottom of this recess and the groove 36 in the distributor 35. Cone-printed screws 40 screwed into the body of the mould shell hold the end unit in place. The refractory lining 41 of the distributor 35 is so shaped that there is provided a flared passage 43 from the pouring aperture 42 and a number of radial passages 44 adjacent the screen. These discharge into an annular passage 45, into which also discharge radial passages 46 located in front of apertures 47 provided in the screen. The apertures 47 are provided in the sand 47^a with which the screen is lined

and are lined with refractory tubular pieces 47^b. The passages 46 are disposed in the passage 45 between the passages 44. According to this construction the assembly of the front part of the mould is materially simplified. Moreover, before it enters the moulding chamber, the molten metal undergoes a zig-zag motion which helps to free it of impurities and in some cases prevents a too sudden inrush of metal into the moulding chamber.

According to another modification, shown in Figs. 8 and 9, a refractory lining is provided which is discarded after each moulding operation. The screen comprises a central portion 48 having a conical or like shape so that this portion offers but a slight resistance to the withdrawal of the moulding head to be obtained. Any longitudinal cracking of this head is thereby avoided. This central portion is connected to a mounting ring 49 by means of arms 50. The ring 49 is housed in a recess provided in the sand 51 forming the refractory lining of the body 52 of the distributor. Owing to this construction, instead of having a number of metal feed apertures, the metal may be distributed in an even manner practically over the whole circumference of the screen. The lining 51 has of course ribs 53 disposed in front of the arms of the screen. The central part of this screen includes adjacent the moulding chamber a blind hole 54 communicating with passages 55 provided in the arms 50. These passages are connected to pipes 56 which are extended along the outer face of the extension 52 and discharge into the atmosphere at 56 adjacent the axis of rotation. These pipes are provided for the evacuation of hot air and gases, and in this case the other end of the mould need not include apertures for this purpose. Owing to this construction, any risk of a projection of molten metal as a result of a false move or an accident, is avoided, for the metal level would be too high in the mould and would be thrown out. The length of the pipes 56 as well as their cooling are such that any metal that would attempt to escape therethrough would solidify before having reached the ends of the pipes.

According to another modification shown in Fig. 10, the valves 19 provided in the end plate 14 may be replaced by radial apertures 57 provided in the wall of the shell between the cup 7 and the end plate 14 and extended by short pipes 58 curved to suit the direction of rotation of the mould and which constitute a suction fan. In this arrangement there results a forced suction of the gases contained inside the mould. As this mould is closed, as hereinbefore mentioned, at its metal entry end, a certain depression is thereby produced inside the mould which favours the degassing of the molten metal and prevents any formation of blow-holes or gaseous inclusions in the cast piece. This device naturally prevents any entry of cold air into the interior of the mould.

As is clear from the foregoing description, the casting is performed in a mould which may be considered completely closed. Thus it is very easy to visualize casting in a controlled inert atmosphere, which is particularly advantageous when easily oxidizable metals need to be cast. To this end there may be provided, as is illustrated in Fig. 11, a feed pipe 59 suitably insulated at 60 and connected to the lower outlet 61 of a ladle 62. This pipe passes through the aperture 63, and the ladle stopper 64 is provided with an axial through-passage 65 which communicates at its lower end with the pipe 59 and at its upper end 66 with a bottle containing inert gas (not shown in the drawing). Adjacent the metal entry aperture 63, the pipe 59 is surrounded by an annular sleeve 68 also connected to the bottle containing inert gas and provided with a circular opening 69 which surrounds the pipe 59. Owing to this arrangement, before commencing the casting operation, the gas may be sent through the passage 65 so as to fill completely the mould, then, after having raised the stopper 64 which opens the opening 61 of the ladle through which the molten metal 70 flows into the rotating mould, the mould may be fed with gas through

the sleeve 67 so as to provoke between the pipe 50 and the opening of the diffuser a zone supercharged with this gas and thereby obtain a total superpressure with the surrounding air. In this way, the gas carried with jet into the mould is solely the desired inert gas.

The invention is not limited to the constructional details herein described and illustrated in the accompanying drawings which have been given merely by way of example. The invention is also applicable to vertical or inclined centrifugal casting and is capable of casting tubular pieces having a shape other than those described. Thus, these pieces, instead of being provided with a reinforced or thickened head adjacent the screen E as shown in Fig. 2, may be cylindrical or provided with a thickened head at the detachable end of the mould, etc. It is obvious, furthermore, that the inner face of the mould instead of being lined with sand may be lined with a completely different material such as, for instance, asbestos or paper, etc. This inner face may even be unlined or provided with a metal lining which may or may not be cooled in order to obtain any desired mode or control of cooling depending on the molten metal employed.

Having now described my invention what I claim as new and desire to secure by Letters Patent is:

1. In a mould rotative about an axis of revolution, for the centrifugal casting of an elongated metallic tubular piece with protection against atmospheric air, said piece being susceptible of undergoing a relatively important longitudinal shrinkage, in combination: a rotative tubular mould shell having two ends and an internal surface concentric to said axis, said internal surface emerging at both of said ends and forming a casting chamber; a hollow distributor chamber attached to one of said ends; said distributor chamber forming a passageway for the molten metal to be cast, and being adapted to impart to the molten metal an angular speed of rotation equal to that of said shell before the metal passes from said distributor chamber into said casting chamber; a first transverse plug device, internal to said internal surface comprising a screen disposed between and separating said casting chamber and said distributor chamber; apertures in said screen for the passage of the molten metal and for communication between said chambers, said apertures being so disposed that they are entirely immersed in the molten metal; housing means for said screen, attached to said shell between said distributor and casting chambers, and fusible means disposed between said housing means and the periphery of said screen and adapted to connect temporarily said screen to said housing means, in such a manner that said screen is released at the end of the casting; whereby said screen, then held fast, relative to the cast piece, by the metal frozen in said apertures, is adapted to follow during the cooling of the cast piece the shrinkage of the latter; at the other end of the shell, a second transverse plug device, at least partially movable to close the casting chamber, and a pushing device operable from the outside of said shell and adapted to move said second plug device longitudinally towards said screen during the cooling of the cast piece, whereby the latter is maintained under longitudinal compression in spite of its shrinkage.

2. A mould as claimed in claim 1, in which said screen comprises a metal disc having a circular periphery; and said housing means comprise in combination: a ring having an inner circular flange, said flange being provided with an annular inner rabbet facing the casting chamber, the periphery of said disc engaging said rabbet; and said fusible means consist in a metallic alloy key between said ring and said disc, said alloy melting at a lower temperature than that of the metal to be cast, whereby said key forms a temporary bond between said disc and said ring.

3. A mould as claimed in claim 2, in which said disc, said flange and said apertures are coated with refractory sand.

4. A mould as claimed in claim 1, further comprising an internal sand coating covering the internal walls of said casting chamber and of said distributor chamber, said screen having its periphery engaged in said sand coating.

5. A mould as claimed in claim 1, in which one of said transverse plug devices comprises at least one exhaust passage in combination with a corresponding valve device, so constructed and adapted that said passage allows the exhaust of the gases and air contained in said casting chamber and prevents the entry of atmospheric air into said casting chamber.

6. A mould as claimed in claim 1, in which said second transverse plug device comprises: a double wall consisting in a first internal wall movable longitudinally within said shell and having at least one gas exhaust vent and in a second outer wall attached to said other end of said mould body; at least one exhaust passage through said second outer wall; a valve device on each said exhaust passage; a tapped axial hole in said second outer wall; said pushing device comprising a screw engaging said tapped axial hole, and abutting said first internal wall, said screw being provided with a driving head outside said shell, whereby the turning of said screw accomplishes said longitudinal compression.

7. In a mould rotative about an axis of revolution, for the centrifugal casting of an elongated metallic tubular piece susceptible of undergoing a relatively important shrinkage upon cooling, said mould comprising an elongated tubular shell having an upstream end and a downstream end, the internal surface of said shell being concentric to said axis and emerging at both said ends and being shaped to form a casting chamber, a distributor attached to said upstream end and provided with a distributor having an upstream intake opening, said chamber being adapted to form a passageway for the metal and to impart to the metal an angular speed of rotation equal to that of said shell, and a screen between said casting chamber and said distributor chamber and internal to said internal surface, apertures in said screen for communication between said two chambers and so disposed that they are entirely immersed in the cast metal, in combination: housing means for said screen, attached to said shell between said distributor chamber and said casting chamber, and fusible means disposed between said housing means and the periphery of said screen and adapted to connect temporarily said screen to said housing means in such a manner that at the end of the casting said screen is free to move inwardly of said casting chamber under the action exerted by the cast piece, said action being an axial traction due to cooling and shrinkage; near the downstream end of said shell, a plug device adapted to close said casting chamber, said plug device consisting in a double wall comprising an inner wall longitudinally movable in said casting chamber and provided with at least one gas exhaust vent, and an outer wall attached to said shell and provided with at least one exhaust vent, closure means on each exhaust vent of said outer wall and constructed and adapted to allow the release of gases from said casting chamber and to prevent the influx of atmospheric air through the exhaust vent of said outer wall; and a pushing device in said plug device, said pushing device being movable relative to said outer wall and being constructed and adapted to engage said inner wall and to displace the latter longitudinally; said cast piece being maintained in said casting chamber under axial compression during its cooling by the inward displacement of said inner wall by said pushing device.
